UNITED STATES PATENT OFFICE.

JAMES HICKEY, OF PORTLAND, OREGON.

HEMSTITCHING ATTACHMENT FOR SEWING-MACHINES.

1,401,109.

Specification of Letters Patent. Patented Dec. 20, 1921.

Application filed November 13, 1917. Serial No. 205,464.

To all whom it may concern:

Be it known that I, JAMES HICKEY, a citizen of the United States, and a resident of the city of Portland, county of Multnomah, 5 State of Oregon, have invented a certain new and useful Improvement in Hemstitching Attachments for Sewing-Machines, of which the following is a specification.

The object of my invention is to provide 10 a simple attachment for the usual type of household sewing machine, by which the latter is adapted for doing hemstitching work. Also so to arrange my attachment that it may be readily attached to the sewing machine, and as readily removed again when 15 not wanted.

I attain my object by an attachment adapted for being supported on the presser-bar of the sewing machine, so that it will be 20 yieldingly held to its work, and may be lifted from working contact with the cloth by the lifting of the presser-bar.

The construction of my device, its attachment to the presser-bar of the sewing machine, and its action when so attached, are 25 illustrated in the accompanying drawings, in which:

Figure I (Sheet 1) is a perspective view of my hemstitching attachment as a whole, 30 showing the same as applied in practice to a sewing machine;

Fig. I^a (Sheet 1) shows the parts carried by one side of the frame of the group of mechanisms B of my device, looking at the 35 same as in Fig. I, with the group of mechanisms A removed;

Fig. II (Sheet 2) is a top view of my device by itself on a larger scale; it is to be noted from this view that my invention 40 comprises two coöperating groups of mechanism, designated A and B;

Fig. III (Sheet 2) is an elevation of the parts carried by the inner side of the frame of the group A;

Fig. IV (Sheet 3) shows a rear side or exterior elevation of group B;

Fig. IV^a (Sheet 6) shows details of parts of the mechanism illustrated in Fig. IV;

Fig. V (Sheet 3) is a partial plan section 50 on the dotted line V—V of Fig. IV;

Fig. VI (Sheet 4) shows a partial front side or interior elevation of group B;

Fig. VII (Sheet 4) is a fragmental plan or top view of group B;

Fig. VIII (Sheet 5) shows a right-end

view of my device as a whole, with reference to its position in Figs. I and II;

Fig. IX (Sheet 6) shows a projection in plan of the rim of the "cam-wheel" included in my device;

Fig. X (Sheet 5) is a cross-section on the dotted line X—X of Figs. IV and V (Sheet 3);

Fig. X^a (Sheet 5) is a cross-section on the dotted line X^a—X^a of Fig. IV (Sheet 3);

Figs. X^b, XI, XII, XII^a, XIII and XIII^a (on Sheet 5), Figs. XIV, XIV^a and XV (Sheet 6) and Figs. XVI, XVII, XVIII, XIX and XX (Sheet 1) show details of construction fully described hereinafter, 70 some of these figures being drawn in section and others in diagrammatic form;

Figs. XXI and XXII (Sheet 4) and Figs. XXIII and XXIV (Sheet 3) illustrate diagrammatically the coöperative hemstitching 75 action of the piercing-needle, or piercer, of my attachment, with the needle of the sewing machine;

Fig. XXV diagrammatically illustrates the hemstitching produced by my attachment;

Fig. XXVI illustrates how a cord may be fastened on the goods by the hemstitches made by my attachment; and

Fig. XXVII shows a detail of construction.

The securing of my attachment to the sewing machine is provided for in the clamping head 37 (see Figs. I and XI, Sheets 1 and 5) of the frame of group A of my attachment, into which head are threaded screws 37^a for clamping my attachment to the presser-bar 36 of the sewing machine.

The work done by my attachment, with reference to one cycle of action, is to pierce 95 a hole in the goods and then so move the goods under the needle of the machine that the needle will make the stitches shown in Fig. XXV (Sheet 3). That is to say, a "piercer" 26 carried by my attachment makes a hole 50 in the goods, the needle 38^a of the machine follows and makes a stitch in the same hole. My attachment then moves the goods sidewise, first in one and then in the opposite direction, during which movement 100

the needle of the sewing machine makes the stitches 51, 52 from and back to the hole 50. My attachment then operates to feed the goods forward, the needle makes a stitch 53 and one cycle of action of my attachment 110

is completed, and in the further work such cycle is repeated until the hemstitching is finished.

My attachment includes a vertically oscillable arm *d* (see Fig. I) made with a forked extremity, by which it is engaged with the set-screw of the needle-bar of the sewing machine; and through such arm *d* the oscillations of the needle-bar of the sewing machine are communicated for operating my attachment.

A bridge plate 39 must be used in connection with my attachment, so as to cover the "feeding dog" of the sewing machine. 15 The bridge plate 39 is fastened to the base plate *mp* of the sewing machine. The moving of the goods under the needle of the sewing machine is accomplished by a bifurcated feed-bar *m*, having teeth *n* on its under side, 20 which bar is caused to bear down on the goods and to move the same sidewise and forward, as mentioned, in completing one cycle of action of my attachment. My attachment is then automatically lifted, by devices provided in the same, so as to lift the feed-bar *m* off the goods; and while so lifted the feed bar is moved back to the point from which it was moved to feed the goods forward. Then my attachment is automatically lowered, so as to bring the feed-bar 25 again into engagement with the goods, and the described cycle of action of my device is repeated. The tension of the usual spring of the presser bar 36 of the sewing machine is utilized to hold my attachment in operative contact with the goods.

With this outline of the operation of my attachment the details of its construction may be more readily described. As mentioned, my device comprises two coöperating groups of mechanism designated by B and A respectively, the parts comprised within the latter group being carried by a frame-plate hinged to the frame of group B, by a 45 hinge 28, as more readily seen in Fig. I.

Describing first the details of group B: This comprises a frame consisting of a base-plate *a*, having a vertical web *a'*, as shown in Fig. XI. The web *a'* is provided with holes 50 *a²*, *a³*, in which are inserted the journal pins *b'* and *c*. (See Fig. X). On the pin *b'* is journaled a cam-wheel *b* made with a shoulered hub *b²* (compare Figs. IV and X) on which is rigidly secured a ratchet wheel 55 *f*; and on the shoulder *b³* is pivoted a vertically oscillable arm *d*, having a forked extremity which is connected with the reciprocating needle-bar 38 of the sewing machine by the usual set-screw of such needle bar. On the arm *d* is pivoted a pawl *e* (see 60 Figs. II and IV) controlled by a spring *e'* and engaging with the ratchet wheel *f*. Thus the motion of the needle bar of the sewing machine is transmitted through the 65 arm *d* and progressively partially rotates

the ratchet wheel *f*, and therewith the cam wheel *b*. The latter is held in the position into which it is so progressively moved by a compressed coil spring *b⁵* (Fig. X).

The function of the cam wheel *b* is to so 70 operate my attachment as to feed the goods sidewise, and in so doing causes the needle to make the stiches 51, 52 illustrated in Fig. XXV.

The cam-wheel *b* has a circumferential 75 groove *b⁴*, formed as shown in the plan projection thereof in Fig. IX. To the underside of the base-plate *a* is pivoted by a headed screw *l*, the feed-bar *m*, the extremity of which is forked so as to accommodate the 80 passage of the needle 38^a, said forked extremities are provided with feed-dogs *n*. See Figs. IV, V and XI. The screw *l* bears in the longitudinal slot *l'* of the base-plate *a*.

On the feed-bar *m* is mounted a pin *o'* 85 on which swivels a swivel-block *o*. The swivel-block projects through the aperture *a⁵* of the base-plate *a*, as more clearly shown in Figs. V and X^b; said aperture being adapted to permit the swivel-block reciprocal and rotary motion therein. The swivel-block *o* is provided with a dove-tailed groove *o²* on its upper face in which relatively slides a plate *j*, pivoted by a screw *k* fixed in the base-plate *a*. On the plate *j* is journaled a cam-roller *g* which bears in the peripheral cam-groove *b⁴* of the cam-wheel *b*. The plate *j* serves as a guide for the swivel-block *o* on the feed-plate. 95

From the plan projection of the cam 100 groove *b⁴* in Fig. IX the lateral movements imparted to the feed bar *m* by the revolution of the cam wheel *b* may be traced; these movements being illustrated in Fig. V by full and broken lines; and the relative travel 105 of the roller *g* in said peripheral groove *b⁴* of the cam wheel is illustrated by *g'* and *g²* in Fig. IX.

The feed bar *m* is provided with a lug *y²* 110 (see Figs. IV^a and XII) to which is pivoted an arm *x* by a screw *y'*. The lug *y²* projects through an aperture *y³* of the base-plate *a*; see Figs. V and VII; said aperture being adapted to permit the lug *y²* lateral motion. 115

On the journal pin *c* is rotatably mounted a cam plate *s* connected by a link *q* with the vertically oscillatable arm *d*. See Figs. IV^a and XIV. On the pin *c* is further rotatably mounted a two-membered or duplex ratchet 120 wheel *u'*. The ratchet *u* has twelve teeth and the ratchet *v* has four teeth, as more clearly shown in Fig. XIV^a. From the cam plate *s* projects a pin *r* on which is pivoted a pawl *t* controlled by a spring *t²*, as shown 125 in Figs. XIII and XIV^a, the free end of which pawl has a laterally projecting toe *t'* (see Figs. XIII and XIII^a) adapted to engage with the teeth *u²* of the member *u* of the duplex ratchet wheel *u'*, so that the rock- 130

ing of the cam plate *s* will cause an intermittent partial rotation of the duplex ratchet wheel *u'*. The member *v* of the duplex ratchet wheel *u'* has four lateral pins *w*, spaced equi-distant, for engaging with a lateral toe *y* on the free end of the arm *x*, pivoted to the lug *y'* of the feed bar *m*, as mentioned. See Fig. XIII^a. The pin *r* of the cam plate *s* has a flat face *r'* (see Fig. XIV^a) and the free end of the arm *x* has a notch *x'* so that the arm *x* may engage with the pin *r* as shown. The dropping of the arm *x* into engagement with the pin *r* of the cam plate *s* is therefore controlled by the rotation of the duplex ratchet wheel *u'*, and can occur only once during each quarter revolution of the latter, for since the ratchet wheel *u'* is given only a $\frac{1}{2}$ turn during each up-and-down movement of the arm *d*, it will take three 20 of such movements to effect said engagement. Then the movement of the cam plate *s* will impart to the feed bar *m* a longitudinal, forward movement, through the engagement of pin *r* with the end of notch *x'* thus feeding the goods forward. In time with said lateral movement of the feed bar the needle of the sewing machine makes relatively the stitch 52 to the right from the hole 50 pierced by the piercer, and then the stitch 25 51 to the left, back to the hole. And, while the roller *g* of the feed bar *m* is traveling in a straight course of the peripheral groove of the cam wheel *b*, the arm *x* is actuated, as described, to move the feed arm forward, 30 causing the needle then to make a stitch 53 to another hole 50 (referring to Fig. XXV), previously pierced at such point into the goods by the piercer 26 of my attachment; and then the cycle of actions of my attachment repeats itself.

The feed bar *m* is released from the goods between each cycle of action and moved longitudinally in the reverse or return direction, as pointed by the arrow *a* in Figs. VI 45 and VII, and is then dropped back on the goods, by the tension of the presser-bar 36 of the sewing machine, for again advancing the goods, as described, by the following devices:

50 As shown in Fig. XI, the vertical web *a'* of the base plate, *a*, is provided with a bracket *z*, in which is journaled a vertical shaft *z'* provided at the lower end with an arm 2, and at its upper end with an arm 4, 55 as shown in Fig. XVI. A stud 6 projects from the web *a'* and thereon is pivoted an arm 5, which is provided with laterally projecting hinge knuckles 5^b (see Fig. XVII), in which is hinged, by a pin 10, an arm 9, 60 having a roller 9^a at one end. A coil-spring 9^b, suitably supported between the arms 5 and 9, causes the extremity 9^c of the arm 9 normally to bear against a stop 5^a of the arm 5, and in this position of the arm 9 its 65 roller bearing end is located to one side of the cam plate *s*. The extremity 5^c of the arm 5 bears in a recess 7^a of a vertically movable lifting bar 7 (see detail of latter in Fig. XV) slidably supported by screws 7^c extending through a slot 7^b of said lifting 70 bar and threaded into the head 37 of the web *a'* of the base plate *a*. See Fig. IV. The lower end of the lifting bar is loosely connected by a screw 8^c with a lever-arm 8, pivoted by a screw 8^b to the underside of the 75 base plate *a*, and the free end of such lever arm bears on the bridge-plate 39, secured by a screw 40 (Fig. I) to plate *mp* of the sewing machine in such way as to cover the feed dog of the latter.

80 The feed-bar *m* has a stud pin 3 (see Figs. VII and XI), and while moving in its forward direction, for advancing the goods a step, the pin 3 will strike the lower arm 2 of the shaft *z'* and rotate the latter into its 85 position in full lines in Fig. VII; then the upper arm 4 of the shaft *z'* bears upon the forward end of the arm 9 and so moves the latter as to bring its roller 9^a over the cam plate *s*. Compare Figs. II and VII.

90 Assuming a stitch 53 into a hole 50 (Fig. XXV) to be the first stitch during the cycle of actions of my attachment, the lateral stitch 51 to be the second, and the lateral stitch 52 to be the third, when the latter 95 stitch is completed, and in time with the up-movement of the needle bar of the sewing machine, my attachment will be operated to move the feed-bar *m* forward, so as to advance the goods a step through the engagement of notch *x'* and pin *r*, and in time with such movement of the feed-bar the roller-bearing end of the arm 9 is positioned over the cam plate *s*. Then the next downward movement of the needle bar, in making another stitch 53, to the newly pierced hole 50 100 in the goods, will so rock the cam plate *s* as to cause the arm 9, and therewith the arm 5, to be tilted as shown in Fig. VI, thereby depressing the lifting bar 7 and causing the lever arm 8 to bear on the bridge-plate 39. Now, since the frame of the group of mechanisms B is rigidly attached by the head 37 to the yielding presser bar 36 of the sewing machine, when the lever arm 8 bears down 110 on the rigid bridge plate 39 it will lift my attachment sufficiently to clear the feed bar *m* from the goods, so that it may be moved back to its initial position.

115 To facilitate the rapid disengagement of the arm 9 from the cam plate *s*, the projection at the top or head of the latter has a portion cut away, as at *s'* in Figs. II and IV^a, and so located as to cause the roller 9^a of the arm 9 to slip from the cam plate *s* 120 when the arm *d* has approximately assumed a position indicated by partial dotted outline *d'* in Fig. VI.

125 The feed-bar *m* is moved back to its initial position in the following manner: During 130

the forward movement of the feed-bar m , which occurs just after stitch 52 has been made, and during the up-movement of the needle bar of the sewing machine, as mentioned, the arm d and the lug y^2 of the feed-bar, and their connections, were positioned as shown in dotted outline in Fig. IV^a; the arm x being still engaged by the pin r of the cam plate s . Then, during the next 10 downward movement of said needle bar the arm d will reversely rock the cam plate s and slide its pin r under and lifting the arm x , the pin r then coming into contact with the lug y^2 of the feed-bar, and moving 15 the feed-bar reversely over the goods back to its initial position. The cam v and studs w are so arranged that the operation of the mechanism for raising the attachment by the lever arm 8 and of the mechanism for re- 20 turning the feed-bar to its advanced position is simultaneous; the dished edge s' of the cam plate s being so arranged that the attachment drops and the presser bar engages the work as soon as it reaches its ad- 25 vanced position.

The described action of my attachment is complete in itself and causes the sewing machine to make the stitches 51, 52, 53 shown in Fig. XXV, if no piercing of the goods 30 with holes 50 is wanted.

The piercing of a hole in the goods, as at 50 in Fig. XXV, is performed by the group 35 of mechanism A, which co-operates with the group of mechanism B, and is timed to act in advance of the making of the stitch 53 by the needle of the sewing machine, and after the goods have been advanced a step, as mentioned. The co-operative actions of the 40 needle 38^a and the piercer 26 are diagrammatically illustrated in Figs. XXI and XXII, and resulting in the making of the stitch 51. Then the needle above the work relatively moves laterally from the piercer, as illustrated in Fig. XXIII, to produce 45 stitch 51, and then the needle and piercer are brought together again as illustrated in Fig. XXIV by the relative movement of the goods back to the right, resulting in the making of the return stitch 52 into the previously pierced hole 50.

In order to permit the needle of the sewing machine to enter the hole 50 made by the piercer 26, the latter has a concaved longitudinal recess 26^a, as shown in Figs. II 55 and V.

The devices for piercing the goods, as mentioned, comprised in the group of mechanism A, are constructed as follows: 12 is the supporting plate or frame, which is 60 through the hereinafter described arrangement of a plate 13, adjustably connected by a hinge 28 to the angular portion of the web a' of the frame of the group of mechanism B, see Figs. I and III. The plate 12 is made with

a vertical slot 25, in which slides a piercer-head 24 having a protuberance 24^a (see Figs. III and VIII) in which the piercers 26, 27 are clamped by set-screws 24^b. The piercer 26 is ordinarily sufficient, the auxiliary piercer 27 being only used when it is desired to 70 pierce first a small hole and then a larger one, as may be deemed preferable when working with certain kinds of goods. A reciprocable plate 29 is slidably supported on the plate 12 by screws 19, threaded into 75 the latter plate 12, and working in the slot 22^a of the said reciprocable plate 29. The reciprocable plate 29 is made with an oblique portion 18 (see Fig. III) having a slot 22^b and a transverse piece 23^b, and the 80 piercer-head 24 has a roller 23 which bears in said slot. The reciprocable plate 29 is controlled by a spring 21 and normally is held by the latter retracted, as shown in full outline in Fig. III. When the reciprocable 85 plate 29 is forcibly moved to the right, with reference to Fig. III, it will cause the lifting of the piercer-head 24. Such movement of the reciprocable plate 29 is effected through the stirrup 14, adjustably secured by screws 90 17 inserted through slots 17^a of the stirrup 14 into the portion 29^a of the reciprocable plate 29. The stirrup 14 is made of a piece provided with hinge knuckles 14^a, to which is hinged the piece 14^c, and a leaf-spring 14^b 95 is adapted to hold the hinged piece 14^c away from the plate 12, as illustrated in Fig. II.

The extremity of the hinged stirrup-member 14^c is made with an eye 14^d, for engaging with a pin 11 projecting from the cam plate s (see Fig. I^a) coaxially with the pin r on the opposite side of said cam plate. Said pin 11 is indicated in Fig. III in dotted outline with respect to its extreme positions, and the path of its motion is indicated in 100 the same figure by the curved broken line 11^a connecting said extreme positions. The swinging stirrup-member 14^c is controlled by a hinged arm 35, pivoted at 35^a in the web a' (see Figs. I^a, VI and XXVII) provided at its lower extremity with a toe 35^b, and its upper end terminating in a dog 36. See Figs. I^a, IV and VI. A spring 60 controls the arm 35 so as to cause the dog 36 to ride on the notched periphery of member v of the duplex ratchet wheel u' , and to drop into the peripheral notches of said member v during the latter's rotation.

When the pivoted arm 35 is not in a notch of the member v of the duplex ratchet 120 wheel u' , it will be positioned as shown by dot-and-dash line in Fig. VI, and its toe 35^b will bear against the hinged member 14^c of the stirrup 14 and hold such member out of engagement with the pin 11 of the 125 cam plate s ; and when the arm 35 drops in a notch of the cam member v it will be positioned in full lines in Fig. VI,

with its toe below the hinged stirrup member 14^c, and the spring 14^b will act to engage this member with said pin 11.

The function of the stirrup connection is 5 to lift and depress the piercer 26 (or the piercers) in time with every cycle of motions of my attachment, which cycle corresponds with three stitches of the sewing machine mentioned. Therefore the coöperating parts are so timed that the stirrup will 10 become engaged with the pin 11 of the cam plate *s* once in each sequence of three movements of the latter.

An inclined trip-plate 34, (see Fig. I^a) 15 affixed on the web or frame portion *a'* of the group B, is adapted to disengage the stirrup 14 from the pin 11 when the latter has almost traveled to the end of its course in the direction pulling the reciprocable bar 20 29 inward and causing the lifting of the piercer 26. In this way the stirrup 14 is suddenly released, the spring 21 then acting to project the reciprocable bar 29 outward, abruptly, and thereby causing the piercer 25 26 to descend and strike the cloth on the bridge plate 39 with sufficient force to go through and make the hole 50.

On the outer face of the plate 12 of the group A is mounted, vertically slidable, a 30 latch-plate 33 provided with a hook 33^a adapted to be engaged with the head 20^a of the screw 20 sliding in the groove 22 (see Fig. I) when the latch-plate 33 is depressed. In this way the reciprocable bar 29 may be 35 latched in retracted position and locked in that position by tightening the thumb-screw 32. The lower end of the latch-plate 33 is made with a latch hook 31 adapted to engage with the slot 30 of the feed-bar *m*, as 40 illustrated in Fig. VIII, so as to lock the group A in coöperative position with the group B.

The reciprocable bar 29 is locked in retracted position, and thereby the piercer in 45 uplifted position, when the group of mechanisms A is to be swung outward from the group B. This is desirable to facilitate the threading of the needle, as evident from the inspection of Fig. I. Group A mechanism is connected slidably to the feed-bar *m* by hook 31, so as to have lateral movement therewith swinging on hinge 28.

The screw 40 is inserted through the hole 40^a of the bridge-plate (Fig. XVIII). 39^a 50 are holes for the needle 38^a of the sewing machine and the piercer 26 of my attachment. 39^b is a reinforcing leg supporting the middle of the bridge-plate, so as to prevent the bending thereof when the stress of lifting my attachment is imposed upon it, this leg of course being of a vertical dimension to avoid interfering with the normal movement usual "feeding dog" of the sewing machine.

A detail of the bridge-plate is shown in 65 Figs. XVIII, XIX, and XX, which, in the order named, show a top view and longitudinal and transverse sections.

It will have been noted that the purpose of the bridge plate 39 is also to provide a 70 surface spaced from the feed dog of the sewing machine through which the piercer 26 may strike in making the hole 50 in the goods.

The arm *x*, as shown in Fig. XII may 75 be made with an adjustable piece *x'*, carrying the tongue and clamped in place by a set screw *x'*. This permits of adjustment to lengthen or shorten the stitches by varying the feed of the cloth. In order to provide 80 adjustment with reference to the varying distance between the presser bar and the needle-bar of different sewing machines, the plate 13 is slidably connected to plate 12 by means of screws 15 bearing in the slots 15, 85 and the plate 13 is clamped in place on the plate 12 by the thumb-screw 15^a bearing in the slot 16^a.

This adjustment is also required when the stitching mechanism and piercer mechanism 90 are connected, since these two mechanisms must be adjusted relatively to the distance between the presser bar and the needle bar of the sewing machine on which my attachment is used.

My stitching attachment may also be used 95 for fastening a cord to the goods by the hemstitches as illustrated in Fig. XXVI. For such purpose the feed bar *m* is provided with an eye, as shown at *m'* in Figs. I and 100 XI, through which a cord 54 may be fed and stitched in place on the goods.

The expression forward, as used in the foregoing specification is to be understood as indicating the direction away from the 105 operator at the front of the machine.

I claim:

1. An attachment of the character described adapted for being fastened to the presser-bar of a sewing machine and comprising means, including a piercer, for making a hole in the goods in which to receive the needle of the sewing machine, means for feeding the goods sidewise and forward from the needle of the sewing machine, and such 110 means adapted to be operatively connected with and operated through the medium of the needle bar of the sewing machine.

2. An attachment of the character described adapted for being fastened to the 115 presser-bar of a sewing machine and comprising means, including a piercer, for making a hole in the goods in which to receive the needle of the sewing machine, means for feeding the goods sidewise and forward from the needle of the sewing machine, such 120 means adapted to be operatively connected with and operated through the medium of 125

the needle bar of the sewing machine, and devices adapted upon the completion of each cycle of action of the goods-feeding means to lift them from the goods and return said feeding means to their initial position.

3. In combination with a sewing machine including a presser-bar and a bridge-plate covering the feed-dog of the machine, an attachment secured to said presser-bar and comprising means, including a piercer, for making a hole in the goods in which to receive the needle of the sewing machine, means for feeding the goods sidewise and forward from the needle of the sewing machine, releasing means including a member bearing on said bridge-plate, thereby lifting the feeding means from the goods in time with each cycle of action of the feeding means, and said attachment being connected with and operated through the medium of the needle-bar of the sewing machine.

4. In combination with a sewing machine including a presser-bar and a bridge plate covering the feed-dog of the machine, an attachment secured to said presser-bar and comprising means, including a piercer, for making a hole in the goods in which to receive the needle of the sewing machine, means for feeding the goods sidewise and forward from the needle of the sewing machine, means for returning said feeding means to their initial position while disengaged from the goods, releasing means including a member bearing on said bridge plate, thereby lifting the feeding means from the goods in time with each cycle of action of the feeding means, and said attachment being connected with and operated through the medium of the needle bar of the sewing machine.

5. The combination with a sewing machine provided with a spring-controlled presser-bar, of a bridge-plate covering the feed mechanism of the sewing machine, and an attachment secured to the presser bar comprising means adapted to feed the cloth relatively to the needle of the sewing machine, means, included in said attachment, comprising a member operated periodically to bear on said bridge-plate and lift said presser-bar and therewith the attachment, thereby disengaging said feeding means from the cloth, and motion transmitting connections between said operating means and the needle bar of the sewing machine.

6. In an attachment of the character described, the combination of a vertically oscillatable arm adapted for connection to the needle bar of a sewing machine, a cam wheel and means for intermittently rotating it operated by said oscillating arm, said cam wheel provided with a peripheral cam groove, a feed bar, a roller mounted thereon bearing in said peripheral groove, a ro-

tatable member intermittently rotated in time with the rotation of said cam wheel, and means controlled by the intermittently rotated member periodically moving said feed bar forward.

7. The combination with a sewing machine, of a bridge-plate covering the cloth feeding mechanism of the latter, and a hemstitching attachment comprising a frame adapted for being fastened to the presser-bar of the sewing machine, a vertically oscillatable arm adapted for connection to the needle bar of the sewing machine, a feed-bar, means operated by said oscillating arm adapted to impart to the feed-bar reciprocal lateral movements and a forward movement in sequence, means for lifting the feed-bar off the goods when its said sequence of movements has been completed, such lifting means including a member bearing on said bridge-plate, and means for retracting the feed bar while lifted.

8. The combination with a sewing machine, of a bridge-plate covering the cloth feeding mechanism of the latter, and a hemstitching attachment comprising a frame adapted for being fastened to the presser-bar of the sewing machine, a vertically oscillatable arm adapted for connection to the needle bar of the sewing machine, a feed bar, means operated by said oscillating arm adapted to impart to the feed-bar reciprocal lateral movements and a forward movement in sequence, means for lifting the feed-bar off the goods when its said sequence of movements has been completed, such lifting means including a member bearing on said bridge-plate, means for retracting the feed-bar while lifted, and means for piercing a hole in the goods for the needle of the sewing machine in time with such sequence of movements of said feed-bar.

9. A hemstitching attachment comprising a frame adapted for being fastened to the presser-bar of a sewing machine, a vertically oscillating arm adapted for attachment to the needle bar of the sewing machine, a feed-bar, means operated by said oscillating arm adapted to impart to the feed bar reciprocal lateral movements and a forward movement in sequence, means for lifting the feed-bar off the goods when its said sequence of movements has been completed, means for retracting the feed-bar while lifted, and means for piercing a hole in the goods in time with such sequence of movements of said feed bar.

10. A hemstitching attachment comprising a frame adapted for being fastened to the presser-bar of a sewing machine, a vertically oscillatable arm adapted for attachment to the needle-bar of the sewing machine, a cam wheel, means operated by said oscillating arm adapted to intermit-

tently rotate the cam wheel, a feed-bar connected with said cam wheel being thereby given reciprocal lateral movements, means for moving the feed-bar forward during the 5 intermittent rest of said cam wheel, means for lifting said attachment after each cycle of said movements of the feed-bar thereby disengaging the latter from the goods, and means for retracting the feed bar while said 10 attachment is lifted.

11. A hemstitching attachment comprising a frame adapted for being fastened to the presser-bar of a sewing machine, a vertically oscillatable arm adapted for attachment 15 to the needle-bar of the sewing machine, a cam wheel, means operated by said oscillating arm adapted to intermittently rotate the cam wheel, a feed bar connected with said cam wheel being thereby given reciprocal lateral movements, means for moving the feed-bar forward during the intermittent rest of said cam wheel, means for lifting said attachment after each cycle of 20 said movements of the feed-bar thereby disengaging the latter from the goods, means for retracting the feed-bar while lifted, and means for piercing a hole in the goods for receiving the needle of the sewing machine.

12. A hemstitching attachment comprising a frame adapted for being fastened to the presser-bar of a sewing machine, a vertically oscillatable arm adapted for attachment to the needle-bar of the sewing machine, a cam wheel, means operated by said oscillating arm adapted to intermittently rotate the cam wheel, a feed-bar connected with said cam wheel being thereby given reciprocal lateral movements, means for moving the feed-bar forward during the 30 intermittent rest of said cam wheel, means for lifting the feed-bar relatively in time with each sequence of its movements, means for retracting the feed-bar while lifted, a vertically reciprocable piercer, a spring 35 adapted normally to project the piercer, means for retracing the piercer, such means timed with said sequence of movements of the feed-bar, and means, also timed with said sequence, for disengaging said piercer 40 from its retracting means.

13. In an attachment of the character described, the combination with means for feeding the goods relatively to the needle of a sewing machine, of a vertically reciprocable piercer, a spring adapted normally to project the piercer downward, means cooperating with the goods-feeding means for retracting the piercer periodically, and means timed with the cycle of action of said 55 goods-feeding means for disengaging said piercer from its retracting means.

14. A hemstitching attachment comprising a frame adapted for being fastened to the pressure-bar of a sewing machine, a

vertically oscillating arm adapted for attachment to the needle-bar of the sewing machine, a feed-bar, means operated by said oscillating arm adapted to impart to the feed-bar reciprocal lateral movements and a forward movement in sequence, means for lifting the feed-bar off the goods when its 65 said sequence of movements has been completed, and means for retracting the feed-bar while lifted.

15. In an attachment of the character described, the combination with means for feeding the goods relatively to the needle of a sewing machine, of a vertically reciprocable piercer, a spring adapted normally to project the piercer downward, means co-operating with the goods-feeding means for retracting the piercer periodically, means timed with the cycle of action of said goods-feeding means for disengaging said piercer from its retracting means, and said piercer 80 being also adapted for being retracted 85 manually.

16. In an attachment of the character described, the combination with means for feeding the goods relatively to the needle 90 of a sewing machine, of a vertically reciprocable piercer, a spring adapted normally to project the piercer downward, means co-operating with the goods-feeding means for retracting the piercer periodically, means 95 timed with the cycle of action of said goods-feeding means for disengaging said piercer from its retracting means, said piercer being also adapted for being retracted manually, and means for locking the piercer in position 100 when retracted.

17. The combination with a sewing machine including a needle, of a bridge plate secured over the feed dog of the former and spaced therefrom, and cloth piercing 105 mechanism carried by the presser-bar of the sewing machine and operated by the sewing machine having a piercer striking through said plate in making a hole in the cloth.

18. In an attachment of the character 110 described, a cloth-feeding bar, means for progressively moving the same in sequence forward and sidewise, such means adapted to be connected to and operated by the needle bar of the sewing machine, and means 115 carried by said cloth-feeding bar for holding a cord in position to be fastened on the cloth by the stitches made thereon.

19. In an attachment of the character described, the combination of means for piercing a hole in the goods in which to receive the needle of the sewing machine, means operating to feed the goods sidewise and back and then forward, and thereby causing the needle to make a stitch laterally from 120 and back into said hole made in said goods and then from the said hole to the succeeding 125 hole made by said piercing means.

20. In an attachment of the character described, the combination of means for piercing a hole in the goods in which to receive the needle of the sewing machine, means operating to feed the goods sidewise and back and then forward, thereby causing the needle to make a stitch laterally from and back into said hole made in said goods

and then from the said hole to the succeeding hole made by said piercing means, means for lifting the feeding means off the goods after its said movements have been completed, and means for returning the feeding means to their initial position while lifted off the goods.

JAMES HICKEY.
